(**) Term: **15 Years**

CLAIM

(21) Appl. No.: **29/579,168**

The ornamental design for a display screen or portion thereof with animated graphical user interface, as shown and described.

(22) Filed: **Sep. 28, 2016**

DESCRIPTION**Related U.S. Application Data**

(63) Continuation of application No. 29/510,013, filed on Nov. 24, 2014, now Pat. No. Des. 774,051.

FIG. 1 is a front view of a display screen or portion thereof with animated graphical user interface showing a first image of the claimed design;

(51) **LOC (10) Cl.** **14-04**

FIG. 2 is a second image thereof;

(52) **U.S. Cl.**

FIG. 3 is a third image thereof;

USPC **D14/488**

FIG. 4 is a fourth image thereof;

(58) **Field of Classification Search**

FIG. 5 is a fifth image thereof;

USPC D14/485-495

FIG. 6 is a sixth image thereof;

CPC G06F 3/048; G06F 3/0481; G06F 3/04817;

FIG. 7 is a seventh image thereof; and,

G06F 3/0482; G06F 3/0483; G06F

FIG. 8 is an eighth image thereof.

3/04842; G06F 3/0485; G06F 3/04855;

The outermost dashed broken lines in the figures show a

G06F 3/0486; G06F 3/0488; G06F

display screen or portion thereof, and form no part of the

3/04886; G06F 9/4443; G06F 17/211;

claimed design. The other dashed broken lines in the figures

G06F 17/212

show portions of the animated graphical user interface that

See application file for complete search history.

form no part of the claimed design.

References Cited

The appearance of the animated images sequentially transitions between the images shown in FIGS. 1-8. The process or period in which one image transitions to another forms no part of the claimed design.
